WINDOW DEVICE

Joseph E. Clay and Walter O. Wille, Cedar Heights, Iowa, assignors to Clay Equipment Corporation, Cedar Falls, Iowa

Application August 21, 1933, Serial No. 685,981

5 Claims. (Cl. 189—69)

Our invention relates to improvements in window devices, and the object of our improvement is to supply a device of this class suitable especially for animal habitations or other buildings, in which a tiltable sash is swingably mounted between spaced closure side wings to adjustably direct air drafts upwardly into the building and being supplied with novel means for releasably securing the sash in a desired position of tilting or held securely in a closed position in the window frame.

This object we have accomplished by the means which are hereinafter described and claimed, and which are illustrated in the accompanying drawing, in which Fig. 1 is a front elevation of the improved window device as seen from within the building, parts being in section or broken away. Fig. 2 is a vertical cross section of the window device taken on the broken line 2—2 of said Fig. 1, and the dotted lines indicating an adjustably opened position of the sash thereof. Fig. 3 is a top plan of the device, with parts in horizontal section, and the sash closed. Fig. 4 is a top plan of the device with parts in horizontal section, and the sash in the same position of tilted adjustment as shown in said Fig. 2 in dotted lines. Fig. 5 is an enlarged fragmentary detail view in section of the lower bearing parts and their swingable sash as mounted thereon for vertical sliding adjustments. Fig. 6 is a perspective detail of the shoulder locking means.

This invention constitutes an improvement upon the window device patent granted to J. B. Clay and L. R. Wilson, by the United States Patent Office, March 7, 1933, Number 1,899,943, and upon the window device, application serial number 595,274, filed February 26, 1932, by J. B. Clay and W. O. Wille.

Our improved window device includes a hollow rectangular window frame of metal preferably shown at 1 in Fig. 2 as a Z-bar in cross section. The bottom reach of this frame has its forward part inclined angularly forwardly. This part of the frame has a depending flange 5 therealong. A sash 8, also preferably of metal, is mounted within the said frame and its parts are of T-bar cross section. These sections of the frame and sash may be of any other desired cross section.

The inner flange of the window frame 1 as detailed in said Fig. 5, is near its lower parts at each side seated in side notches 8b of rectangular shape of the lower angular part of the sash loosely, the said part being bent downward-

ly at 8a, and the notches have their edges at a right angle relatively to each other to permit the lower cross bar of the sash 8 to be slid upwardly on the said flanges of the frame 1, and also to make the sash tiltable forwardly. On the inner face of the lower sash bar may be fastened a downwardly hooked finger-piece 18 conveniently placed and for use in lifting the sash upwardly. The sash may have one or more panes as desired, and the bounding bar parts 65 thereof are preferably also of T-bar cross section.

Within the window frame 1 and between its sides and the adjacent side bars of the sash 8 are the substantially triangular metal side wings 6, imperforate, and widening upwardly, and having along their inner sloping edges the inwardly directed flanges 7 which are opposite each other to serve as limiting stops for the swingable sash 8. The lower edges of the wings 6 and said flanges 7 are seated within the frame 1 at the bottom and the flanges 7 contact with the front part 5 of the frame at the same angle of inclination. The wings 6 are secured to the window frame in any desired manner as by rivets or bolts. If and when desired, angle braces 19 are fixedly connected between the top horizontal edges of the wings 6 and the upper bar of the frame 1, as shown in said Fig. 4.

On the inside face of each wing 6 at or near its top a curving friction-lock bar 16 is mounted thereon in spaced relation on interposed studs 17, both ends of the bar 16 being preferably spaced either from the flange 7 or in the rear from the frame 1, and in the latter case with an abrupt vertical shoulder, and slightly in advance of the top bar of the sash 8 when closed. This top bar of the sash as shown in Fig. 1 has a medial apertured pair of lugs 12 and near its ends with a single apertured lug 14 whose apertures are in line with the apertures of the lugs 12 to seat therethrough the separated but aligned members of a rock shaft 13 which has a medial elongated loop or handle part 11.

The numeral 10 denotes a pair of hooks mounted fixedly centrally on the middle horizontal bar of the sash 8, and the detents thereof face each other in spaced relation, whereby when the resilient rod parts of the handle 11 are compressed toward each other sufficiently, the parts may be brought between the detents inwardly and then released to expand to grip the inner faces of the detents when the sash is to be secured in a closed position, or in any adjustably tilted position by means now to be described.

110

The extreme end parts of the shaft members 13 without the bearing lugs 14 are bent to be cranks 15 whose terminations cross the rear shoulders of the friction-bars 16 when the sash 5 is closed to grip the shoulders and lock the sash to the frame 1. This is shown in full lines in Fig. 2, also in Fig. 3. When the sash is to be held 10 releasably in a tilted position adjustably, as shown in Fig. 4 in full lines and in said Fig. 2 in dotted lines, the handle 11 having been first disengaged from the clips 10 is rocked forwardly to disengage the said terminal cranks 15 from behind the rear shoulders of the friction bars 16, so that the cranks will just clear the lower edges of 15 the bars 16 as the sash is swung forwardly to a desired position. Then the handle is reengaged as described with the clips 10, which rocks the cranks 15 upwardly to tightly frictionally grip the lower edges of the bars 16, thus holding the 20 sash in its adjusted position.

The reinforced mounting of the wings 6 and including the friction-bars 16 afford a strong and rigid construction to retain the sash in an adjusted position.

25 Having described our invention, what we claim as new, and desire to secure by Letters Patent, is:

1. In a window device, in combination, an open window structure, a sash swingingly mounted therein, spaced side wings mounted on said structure with the sash movable between them, a bar with a curvate longitudinal edge and secured in spaced relation across the top part of the inner wall of a wing, a crank rockingly mounted on said sash to be rocked into frictional engagements with the curvate edge of said bar at times, and means for releasably locking said crank in any of adjusted engagements with said bar to hold releasably said sash in a desired tilted position.

30 2. In a window device, in combination, an open window structure, a sash swingingly mounted therein, spaced side wings mounted on said structure with the sash movable between them, like bars with curvate under edges secured in spaced relation across the top parts of the inner walls of said wings, a rock-shaft mounted across said sash and provided with like end cranks for oc-

casional engagements adjustably with the curvate edges of said bars, and means for releasably locking said rock-shaft to hold said cranks in engagement with said bars to retain the sash in a desired tilted open position.

3. In a window device, in combination, an open window structure, a sash swingingly mounted therein, spaced side wings mounted on said structure with the sash tiltably movable between them, like bars with curvate under edges secured across the top parts of the inner walls of said wings, a rock-shaft mounted across said sash and provided with end cranks, the rear ends of said bars being spaced from said sash when the latter is closed, said rock-shaft having a medial lever-handle, means for locking said handle in an adjusted position, and said cranks when rocked being adapted to either engage the rear ends of said bars to lock the sash in closed position, or to engage the curvate edges of the bars to lock the sash in desired tilted positions of adjustment.

4. In a device of the character described, a window frame, a sash tiltably mounted therein, a curvate element mounted upon the window frame with a radius of curvature slightly longer than the radius of tilting movements of the sash, said curvate element being shaped with an abrupt shoulder spaced from said frame, and a rockable element mounted upon the sash to be engaged at times lockably and releasably with the said shoulder to retain the sash in a closed position, and at other times to be rocked into locking engagements with the curvate bar to releasably retain the sash in a desired position of tilting relative to said frame.

5. In a device of the character described, a window frame having engaging means rigidly mounted thereon, a sash swingingly mounted in said frame, and a rockable arm mounted on the sash with means thereon for engaging it releasably with a part of the frame engaging means to hold the sash in a desired adjusted tilted position, or interlocked with an end part of said engaging means releasably when the sash is close upon the frame.
